UNITED STATES PATENT OFFICE.

GEORGE H. FELT, OF NEW YORK, N. Y., ASSIGNOR TO THE FELT ELECTRICAL COMPANY, OF SAME PLACE.

GALVANIC BATTERY.

SPECIFICATION forming part of Letters Patent No. 429,895, dated June 10, 1890.

Application filed November 18, 1889. Serial No. 330,118. (No model.)

To all whom it may concern:

Be it known that I, GEORGE H. FELT, a citizen of the United States, residing in the city, county, and State of New York, have invented a new and useful Improvement in Primary Cells or Batteries, of which the following is a specification.

My invention is concerned with improvements in primary cells or batteries of the two-liquid type, and covers certain details of construction, which will be fully described in the specification which follows, and more particularly pointed out in the claims. The cell which I show and describe is of the class in which the two electrodes are located one above the other in the exciting-liquid; but this feature is not essential, and the electrodes may be located side by side with a vertical partition between them instead of being placed one above the other with a horizontal separating-wall.

In my invention I sustain one liquid in a removable receptacle formed of bond or parchment paper. I prefer to use this substance because I find in practice that it offers little or no perceptible resistance to the passage of the current through the cell, while at the same time it keeps the liquids from intermingling. This property I find very useful and important for my purposes. Some distance below the top of the jar is reduced in size, so as to form an interior ledge on which the bond-paper diaphragm constituting the receptacle for one of the liquids is supported. The portion of the jar above the ledge forms a chamber within which the diaphragm is contained. The upper part of the diaphragm is pressed against the inner surface of the chamber by a hoop or ring of hickory or other elastic material, between which and the diaphragm is a band of waterproof paper or similar material, to provide an additional safeguard against the mixing of the liquids by reason of their creeping up the sides and over the edges of the diaphragm. The band referred to effectually prevents such creeping and insulates the liquids. The band and hoop also help to give the necessary stiffness for rendering it possible and easy to remove the diaphragm and its contents. By a special coupling arrangement, which will be described hereinafter, I

am able to preserve the continuity of the band all around the vessel without leaving an opening at the joint. Below the ledge referred to is a chamber of considerable size and below that another of still smaller diameter. On the ledge which divides the last-named chambers I support perforated metallic plates or sheets of wire-netting and press them down into contact with the negative electrode in the lowermost chamber.

In setting up my battery my cathode, consisting, preferably, of a bunch of copper plates joined together, so as to present as much surface as possible to the action of the liquid, is placed in the lowest chamber and an insulated wire is carried from it along the walls of the jar and out at the top. The perforated plates or sheets of wire-netting are then put in place on the lower ledge and pressed and held down by an elastic hoop, say, of hickory. After this an exciting-liquid, preferably consisting of a sulphuric-acid solution, is poured in until it passes slightly above the top of the middle chamber. The diaphragm is then set in and the hickory hoop inserted with the band of water-proof paper between the two. The pouring in of the upper liquid—say sulphate of zinc—and the insertion of the anode, which is preferably of zinc in the form of a circular grate having a grooved upper surface for containing mercury to keep the electrode amalgamated, completes the process. One or more tubes between the diaphragm and the wall of the jar for assisting in the replenishing of the liquid in the lower chamber and for admitting of the escape of gas therefrom may be added, though they are not absolutely essential.

I have illustrated my invention in the accompanying drawings, in which—

Figure 1 is a vertical section of a battery-cell constructed in accordance with my invention. Figs. 2 and 3 are respectively details of the positive and negative electrodes on a reduced scale, and Fig. 4 is a detail perspective of the water-proof band.

Referring to the drawings by letter, A is the jar, made of some good insulating material, preferably glass.

B is the upper chamber of the jar, C the middle, and D the lower chamber. In the

chamber D is the negative electrode E, which consists of a series of leaves or plates *e*, preferably of copper, joined centrally and bent out, as shown, so as to present as much 5 surface as possible to the exciting-liquid F. The extremities of the plates or leaves are so bent as to press against the sides of the jar and hold the electrodes firmly in place. Their tops extend slightly above or at least as high 10 as the top of the ledge, which separates the middle and lower chambers. A liquid which surrounds the negative electrode is preferably a sulphuric-acid solution. It fills the lower chamber and also the chamber C, extending 15 slightly beyond the same, as will presently appear. At the top of the chamber D is a ledge or shoulder *c*, on which is supported one or more (in this instance, two) perforated metallic plates or sheets of wire-netting G. The wire-netting or its equivalent, when of copper, as I prefer for battery purposes, forms, practically, an extension of the cathode. A hoop J, of hickory, holds the plates G against the top of the copper plates, 20 which form the body of the cathode.

In the upper chamber B is contained a diaphragm H, preferably of bond or parchment paper. This diaphragm is formed into a receptacle the walls of which rest against the 30 inner surface of the chamber B. Within the rim of the diaphragm is a band *l* of some water-proof substance—such as stiff water-proof paper—which is pressed against the diaphragm by an elastic hoop or ring L, say of hickory. From Fig. 4 it will be seen that the band is slit at *s* and that one end is folded longitudinally in a double fold and passed through the slit. The folds are afterward removed and then one end laid along the body 40 of the band, the other end being left long enough to pass around and cover the joint at the slit.

At K is shown the positive electrode in the shape of a circular grooved grate, the grooves 45 of which are filled with mercury. I find that the application of mercury in this way is quite sufficient to amalgamate the entire surface of the zinc below the liquid. The binding-posts *k*, of which I have shown four, are 50 for obvious reasons arranged far enough from the edge of the grate to escape touching any part of the receptacle.

M is a tube which passes down between the diaphragm H and the inner wall of the 55 jar. This tube can be used in supplying the lower liquid either in the first instance or when it has run low. In general, however, the filling is accomplished by the process already described, and when the liquids are to 60 be changed the upper receptacle with its contents is removed and the jar emptied, after which the refilling takes place by precisely the same process. The tube or tubes may do service in permitting the escape of the gases

set free in the lower and middle chambers by 65 the decomposition at the lower electrode.

When the receptacle H is put in place, the liquid below is forced up along the sides about as high as the top of the liquid within the diaphragm. Thus the pressure of the 70 liquids is about equal on both sides of the diaphragm.

An insulated wire *w* passes from the lower electrodes up through the jar, traversing the lower liquid and passing next to the wall of 75 the jar outside the diaphragm.

Having now described my invention, what I claim is—

1. In a galvanic battery, an insulating cell or jar and a cathode of copper plates joined 80 centrally and bent apart at the edges, the length and arrangement of the plates being such that their ends press against the sides of the jar and hold the cathode in place, as set forth.

2. In a galvanic battery, a cathode of vertical copper plates joined centrally and bent apart at the edges, in combination with one or more horizontal copper plates forming an extension of the cathode.

3. In a galvanic battery, a cathode of vertical copper plates joined centrally and bent apart at the edges, in combination with one or more perforated horizontal copper plates forming an extension of the cathode, as set 95 forth.

4. In a galvanic battery, a cathode of vertical copper plates joined centrally and bent apart at the edges, in combination with one or more horizontal copper plates, and a spring 100 holding the horizontal plates in contact with the vertical plates, as set forth.

5. In a galvanic battery, a jar or cell having an interior ledge or shoulder, a diaphragm resting on the said ledge and held against the 105 walls of the jar by a spring, in combination with a band of water-proof material between the spring and the diaphragm, as set forth.

6. In a galvanic battery, a diaphragmatic receptacle containing one of the battery-liquids, a spring pressing the diaphragm against the walls of the battery jar or cell, and a band of water-proof material within the diaphragm, as set forth.

7. The combination, with a battery-cup, of 115 an interior band or lining of water-proof material, the said band being slit and having one of its ends passed through the slit and laid along the body of the band and the other end brought around to cover the joint at the 120 slit, as set forth.

In testimony whereof I affix my signature in presence of two witnesses.

GEORGE H. FELT.
